UNITED STATES PATENT OFFICE.

ANTOINE VAN DEN PLAS, OF WOLUWE-ST. PIERRE-LEZ-BRUSSELS, BELGIUM.

SUPPORT FOR PROJECTORS OR LAMPS PARTICULARLY FOR MOTOR-VEHICLES.

1,100,506.

Specification of Letters Patent. Patented June 16, 1914.

Application filed October 3, 1912. Serial No. 733,784.

To all whom it may concern:

Be it known that I, ANTOINE VAN DEN PLAS, a subject of the King of Belgium, and a resident of 32 Rue St.-Michel, Woluwe-
St. Pierre-lez-Brussels, Belgium, have invented new and useful Improvements in Supports for Projectors or Lamps Particularly for Motor-Vehicles.

This invention relates to an improved arrangement for supporting lamps and projectors especially for lamps arranged on either side at the front of a motor vehicle.

Hitherto the lamps or projectors of motor vehicles have been mounted upon supports in the form of a fork, the vertical arms of which fitted into orifices in two ears secured on either side of the lamp. Such supports have many disadvantages from a practical and also from an esthetic point of view. In the first place they increase the breadth of the lamps and therefore necessitate their being put in front of the radiator where they interfere very much with the driver operating the starting handle. Besides when the lamps are taken off, the forked supports may injure the driver's arm or head when he is working the starting handle. Finally this method of supporting the lamp by ears resting on the two arms of a fork necessitates

the arms being set at precisely the proper distance apart, a distance which varies according to the dimensions of each lamp; and also the height of the supporting shoulders on the arms must be precisely correct as well as the position of the supporting surfaces on the ears. This special adjustment is very expensive for such forked supports and such supports do not permit of different sized lamps being interchanged. Further, the ears

by which the lamp is supported form projections which make the cleaning of the lamp difficult. If the lamp is supported, in accordance with the present invention, upon a central or axial stem which is not forked, all or most of these disadvantages are avoided, the space taken up by the lamp is considerably reduced by the omission of the ears and of the arms of the fork so that the lamp can be placed between the bonnet and the mud-guard without extending in front of the radiator and therefore without interfering with the starting of the engine. Further, lamps of different sizes supported in this manner are interchangeable.

According to the invention, the supporting member of the lamp consists of a solid or

tubular stem, one end of which has an extension which exactly fits the body of the lamp either within it or outside and either above, below, or at the back and which is soldered, riveted or otherwise attached to the body. The other extremity of this stem is a turned boss partially threaded, which engages in a corresponding eye in a supporting arm secured upon the chassis.

The accompanying drawings illustrate by way of example various methods of construction according to the invention.

Figure 1 is a side elevation showing an electric lamp provided with a support consisting of a straight central stem secured to the outside of the lamp body by a riveted and soldered arc the support itself resting upon an arm fixed to one of the side members of the chassis. Fig. 2 is a partial section on the line 2—2 of Fig. 1. Figs. 3 and 4 are views similar to Figs. 1 and 2 respectively save that the arc secured to the lamp is inside it, the lamp is shown in Fig. 3 as being supplied either electrically or with acetylene. Figs. 5 and 6 are views corresponding with Figs. 3 and 4 respectively in which the supporting arc consists of a metal plate riveted to the support which is pressed resiliently against the inner surface of the body of the lamp, (the curvature of which is greater than that of the resilient plate when free) by means of a nut pressing against the outside of the body of the lamp; there are projections on the face of the plate fitting into corresponding recesses in the wall of the lamp body. Fig. 7 shows in side elevation, partly in section, a lamp, the supporting member of which is secured to its rear wall, and Fig. 8 is a partial vertical section on line 8—8 of Fig. 7.

In these various figures, *a* indicates the central preferably cylindrical support ending in arc-shaped lateral extensions *b b* which form a supporting arc forged in one with the support (Figs. 1, 2, 3, 4, and 7) or a separate arc riveted to the support. This arc fits against the outer surface of the lamp body (Figs. 1, 2,) or against the inner surface (Figs. 5 and 6). It is fastened to the body *c* by rivets (Figs. 1, 2, 3, 4, 7 and 8) but it may be independent of the body and have upon its contacting surface buttons or projections *l* fitting into corresponding recesses *m* formed in the body *c* of the lamp (Figs. 5 and 6).

In the arrangement shown in Figs. 5 and

6 the arc *b b* consists of a springy metal plate having at its center a hole through which passes a projection of the support *a* in the form of a rivet *u*. This plate *b b* 5 has a less curvature than the interior surface of the lamp against which it is to be pressed so that the screwing of nut *r* upon the threaded part *s* of the stem *a* causes the plate *b b* to be pressed resiliently against 10 the interior surface of the lamp. Buttons *l l* provided on the contacting faces of the plate are forced by the action of the nut into recesses *m* formed in the wall of the lamp body so as to make the arc solid with 15 the lamp body. It may be seen that the nut *r* presses against a shoulder *q* which surrounds the opening through which the stem *a* projects into the body *c* of the lamp. In the various forms of construction the support *a* 20 terminates at its other end in a reduced portion *d* which may be provided with a spur *v* and may be partially threaded at *e*. This threaded portion enters an eye *f* formed at the end of an arm *g* which is 25 preferably curved and in Figs. 1 to 6 is formed in one with a foot *h* bolted to the side member *i* of the chassis. This foot may have an eye *j* to receive the end of an arm *k* forming the front support of the 30 front mudguard.

The eye *j* has been indicated in the foot *h* in the Figs. 1 to 6 to show that the support *a* of the lamp may be placed opposite the support *k* of the mudguard, that is to say 35 much farther back than has been possible hitherto. In practice this new arrangement for supporting the lamp permits of the lamp

being readily fitted into the space between the mudguard and the radiator of a machine in such a fashion as not to extend beyond 45 the front of the radiator.

Having now particularly described and ascertained the nature of my said invention and in what manner the same is to be performed, I declare that what I claim is:

1. A lamp bracket of the character described comprising a central standard, arc-shaped laterally extending flaps integrally made with said standard at the top thereof, adapted to be resiliently pressed against the 50 face of the lamp body, and a supporting socket secured to the chassis of a vehicle adapted to receive the lower screw-threaded end of said standard, substantially as described.

2. A lamp bracket of the character described comprising a central standard provided with a threaded portion, a curved resilient plate riveted at its center to said standard, and having a curvature of a 60 greater diameter than the curvature of the inner surface of the lamp body, a collar on the lamp body and a nut upon said threaded portion exerting a pressure upon said collar for forcing said plate against said inner 65 face of the lamp body, and means for securing said plate to said lamp body.

Dated this 16th day of September 1912.

In testimony whereof I affix my signature in presence of two witnesses.

ANTOINE VAN DEN PLAS.
